UNITED STATES PATENT OFFICE.

SVERRE THÜNE, OF SKOEN, NEAR CHRISTIANIA, NORWAY.

SCREEN FOR WOOD PULP, ETC.

Application filed December 12, 1924. Serial No. 755,406.

To all whom it may concern:

Be it known that I, SVERRE THÜNE, a subject of the King of Norway, residing at Skoien, near Christiania, Norway, have invented certain new and useful Improvements in Screens for Wood Pulp, Etc.; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

The present invention has for its object a screen for wood pulp, etc., and comprises a screening drum which rotates rapidly in a closed casing. The pulsations which serve to keep the screening surface clean are produced by giving the inner surface of the casing enclosing the screening drum such a form that the distance between the said inner surface and the screening drum is alternately shorter and longer.

Two forms of the invention are illustrated on the drawing, where

Figs. 1 and 2 show cross sections of the said two forms.

1 is the casing which is made in the form of a closed vessel with six edges or extensions and is provided with intake 2 and outlet 3. 4 is the rotating screen which at suitable intervals is provided with radial vanes 5. The casing 1 as stated above has not a regular cross section, but as illustrated on the drawing is extended at the top (6) between intake and outlet and is provided at the top with an air intake tube 7. The inside of drum 4 is provided with an outlet for screened pulp as indicated at 8.

On Fig. 2 is illustrated another form of outlet for the screened pulp. According to this form of the invention the pulp is removed by means of a stationary curved tube 10.

The apparatus operates in the following manner:

The unscreened pulp is introduced at 2 and is caused by means of the rotating drum with vanes 5 to flow with high velocity in the annular space between screening drum 4 and casing 1. The centrifugal force will cause the liquid pulp to follow the inside surface of the casing and fill the space between screening drum 4 and the wall of the casing. Owing to the varying distance

between the screening surface and the inside surface of the casing, the pulp liquid will be caused to pulsate in both directions through the screen openings, whereby the desired screening effect is increased.

It has been proved advantageous, particularly with the form illustrated on Fig. 1, to provide an air intake tube, at the top of the casing.

The air sucked in through tube or tubes 7 will pass through the openings in the screening drum and form an air bubble 9 inside the drum. This air bubble reduces the depth of liquid, whereby a very effective cleaning of the screening surface is obtained. This effect is most prominent at the top of the screening drum, where the casing is also provided with the above mentioned extension 6 in order that the screening surface shall be completely free from pulp liquid, before coming in touch with the new pulp, introduced at intake 2. The radial depth of liquid inside the screening drum may be reduced by mounting one or more stationary outlet tubes 10 (see Fig. 2) which are so curved as to take up and conduct the screened pulp to the outlet.

Claims:—

1. Screen for wood pulp, etc., comprising a closed casing, an intake for unscreened pulp therein, a rotating screening drum mounted inside said closed casing, an outlet for screened pulp from the inside of said rotating drum, the inner surface of said closed casing having such a form that the radial distance between said inside surface and the screening surface varies along the circumference of the casing.

2. Screen for wood pulp, etc., comprising a closed casing, an intake for unscreened pulp therein, a rotating screening drum mounted inside said closed casing, an outlet for screened pulp from the inside of said rotating drum, the inner surface of said closed casing having such a form that the radial distance between said inside surface and the screening surface varies along the circumference of the casing and being also provided with one or more enlargements which are wider than the rest, with the object of obtaining a thorough cleaning of the screening surface one or more points.

3. Screen for wood pulp, etc., comprising a closed casing, an intake for unscreened pulp therein, a rotating screening drum mounted inside said closed casing, an out-

let for screened pulp from the inside of said rotating drum, the inner surface of said closed casing having such a form that the radial distance between said inside surface and the screening surface varies along the circumference of the casing and an air intake at the top of the closed casing with the object of forming an air-bubble, so as to reduce the depth of liquid above the highest point of the screening drum for the purpose of obtaining a thorough cleaning of the screening surface at this point.

4. Screen for wood pulp, etc., comprising a closed casing, an intake for unscreened

pulp therein, a rotating screening drum 15 mounted inside said closed casing, an outlet for screened pulp from the inside of said rotating drum, said outlet having the form of a scoop, adapted to carry away the rotating liquid, the inner surface of said closed 20 casing having such a form that the radial distance between said inside surface and the screen surface varies along the circumference of the casing.

In testimony that I claim the foregoing 25 as my invention, I have signed my name.

SVERRE THUNE.
